UNITED STATES PATENT OFFICE.

THEODORE DIXON AND PETE GRIGSBY, OF WEST BADEN, INDIANA.

INTERNAL-COMBUSTION ENGINE.

1,103,571.

Specification of Letters Patent. Patented July 14, 1914.

Application filed November 4, 1911. Serial No. 653,496.

To all whom it may concern:

Be it known that we, THEODORE DIXON and PETE GRIGSBY, citizens of the United States, and both residing in the town of 5 West Baden, county of Orange, and State of Indiana, have invented certain new and useful Improvements in Internal-Combustion Engines, of which the following is a specification.

10 The invention relates in general to internal combustion engines, and more particularly to the valve means for introducing a charge of gas into the cylinder or cylinders of an engine and for expelling the exhausted 15 or burnt charge.

The principal object of our invention is to simplify the construction of a gas engine by reducing the number of working parts and increasing the efficiency of its operation.

To these ends the invention consists generally in providing the cylinder of an internal combustion engine with a rotatable inner cylinder in which the piston works; 25 the inner cylinder being provided with a single port in registering alinement with suitable ports leading into the combustion chamber of the cylinder, whereby the rotation of said inner cylinder opens and 30 closes said ports for the introduction and discharge of new and burnt gases, respectively.

A further object of our invention is to provide simple, efficient and economical 35 means for operating the inner cylinder.

Further objects of the invention will appear throughout the specification and will be more specifically pointed out in the claims.

40 In the accompanying drawings, Figure 1 is a side elevational view of a two-cylinder engine showing our improved construction; parts being broken away and other parts in section; Fig. 2 is a fragmentary sectional 45 view on the line 2—2 of Fig. 1; Fig. 3 is an end elevational view of Fig. 1 with parts broken away and other parts in section; Fig. 4 is an elevational view of the cylinder head with a part broken away; 50 Fig. 5 is an elevational view of the inner cylinder.

Referring now more particularly to the drawings, the crank case 6 is preferably made in two sections, the lower section 6^a being secured to the upper section by means

of suitable bolts 6^b. Secured to the crank case are the fixed cylinders 7 and 8, which are preferably cast integral and are circumferentially recessed at 9 to form a water-jacket. Each cylinder is provided with a cylinder head 10 centrally recessed to receive suitable spark plugs 11 and provided with compression rings 12. Each cylinder head is provided with intake openings 13 and 13^a and exhaust openings 14 and 14^a, 60 said intake openings communicating with each other and with an intake passage 15 formed through the wall between the cylinders. Registering ports 16 and 16^a are formed through the cylinder wall and in 65 registering alinement with the ports 14 and 14^a. The crank shaft 17 is mounted in suitable bearings in the crank case and, in the construction shown, is provided with two crank arms 18 and 18^a. The connecting rods 19 and 19^a are pivotally connected between the crank arms 18 and 18^a, respectively, and are pivotally connected to suitable piston heads 20 and 20^a. Interposed 70 between the pistons and the fixed cylinder 75 walls are the inner cylinders 21 and 21^a, each being provided with an annular shoulder 22 having a bearing upon annular shoulders 23 formed near the top of the fixed cylinders, thereby preventing relative vertical 80 movement between the outer and inner cylinders when the cylinder heads 10 are secured to the fixed cylinders. Each inner cylinder is provided with circumferential beveled 85 teeth 24 and 24^a at their lower edges, for 90 the purposes hereinafter described.

A gear 25 is mounted upon the crank shaft 17 and is in mesh with a larger gear 26 mounted on a suitable shaft 27, the ends of 95 which shaft are journaled in the side walls of the gear casing 27^a. Said gear casing is mounted upon a suitable support 28 formed on the lower half 6^a of the crank chamber. The gear 26 is provided, on each side thereof, with teeth 29 and 29^a for engagement with the teeth 24 and 24^a on the inner cylinders 20 and 20^a, respectively. Each inner cylinder is provided with a suitable port 30 and 30^a. When the cylinder heads are fastened to the cylinders by any suitable means, such as by machine screws 31, it is obvious that the inner cylinders are confined as to vertical movement, but are free to rotate relative 100 to the outer cylinders.

105 A cylinder may be readily cleaned by re-

moving one of the heads 10, but since the head prevents upward movement of the inner cylinder it is necessary to provide means for holding the teeth 24 and 24^a in engagement with the teeth on the gear 26. To this end threaded apertures are formed through the walls of the fixed cylinders with which set screws 32 have a threaded engagement, the ends of the screws entering grooves 33 formed circumferentially of the inner cylinders. No strain, however, comes upon the set screws when the heads are secured.

The operation of the engine is as follows: Assuming that suitable means are provided, such as a carbureter, for supplying the cylinders with a charge of gaseous mixture and a supply pipe from said carbureter communicates with the port 15, upon a rotation of the crank shaft 17 the pistons 20 and 20^a will be alternately moved up and down within their respective cylinders. This rotation of the crank shaft also rotates the gears 25 and 26, thereby rotating the inner cylinders 21 and 21^a. These cylinders are rotated in opposite directions, as will be readily seen from a reference to Figs. 1 and 2; the piston 20^a in Fig. 1 being shown at the limit of its upward stroke and the port 30^a about to cross the intake port 13^a. Upon a downward movement of the piston 20^a a charge of the gaseous mixture is drawn within the cylinder 7 while the port 30^a is passing the port 13^a; and it will be noted that at this period the inner cylinder closes the exhaust port 16^a of the outer cylinder 7. Upon one upward stroke of the piston 20^a the charge is compressed, and then fired and upon the succeeding upward stroke of the piston the port 30^a passes the port 16^a; the upward stroke of the piston thereby driving out the exhaust gases in the cylinder 7 through the port 16^a. The piston 20 in cylinder 8 is shown at the limit of its downward stroke and by reference to Fig. 2, the port 30 of the inner cylinder is just about to pass the port 16 as the inner cylinder 21 moves in the same path as do the hands of a clock (as viewed in Fig. 2), whereas, the inner cylinder 21^a moves in the opposite direction. It will be therefore seen that as the exhaust charges are about to be driven out from the cylinder 8 a new charge is about to be introduced into the cylinder 7 so that the two cylinders work alternately as to the introduction and discharge of new and exhaust gases. No oiling means are shown for lubricating the inner cylinders but this is

an expedient that may be accomplished in various ways.

While we have shown our invention as applied to a two-cylinder engine, it is obvious that so far as the inner cylinder is concerned, it may be applied to one or more cylinders as desired. Where four cylinders are used it would simply be a duplication of our present structure as shown.

Without confining ourselves to the specific details of construction, nor to a two cylinder engine alone, we claim:

1. An internal combustion engine having in combination a fixed cylinder provided with intake and exhaust ports and having an annular shoulder near its upper end, a second cylinder rotatably mounted in said fixed cylinder and provided with an exterior annular shoulder adapted to rest on the shoulder of said fixed cylinder and with an interior annular shoulder, a port in said second cylinder in registering alignment with the ports of said fixed cylinder, a head for said cylinders extending over the ends thereof and having an extension entering said second cylinder and bearing against the interior shoulder thereon, ports in said head in registering alignment with the ports in the fixed cylinder, a piston in said second cylinder and means for rotating said second cylinder.

2. In an engine, the combination with a plurality of cylinders each provided with inlet and exhaust ports and each having the upper end thereof enlarged circumferentially to form a shoulder, a piston adapted for reciprocation within each cylinder, and a crank shaft common to all of said pistons, of a valve within each cylinder and rotatable therein between the cylinder wall and the piston and having the upper end thereof enlarged circumferentially to fit the similarly formed portion of the inner wall of the cylinder and forming a shoulder resting upon the first mentioned shoulder, each valve being provided with a plurality of ports adapted to register with the ports in the respective cylinder, driving connections between all of said valves whereby the same will operate simultaneously, and driving connections between said crank shaft and valves.

THEODORE DIXON.
PETE GRIGSBY.
